MEANS AND METHOD OF POSITIONING
PLASTICSStanley S. Dodds, San Benito, and James D.
French, Austin, Tex.

Application April 18, 1932, Serial No. 606,056

1 Claim. (Cl. 94—46)

The invention relates to an improvement in means and method of positioning plastics, such as concrete and other similar substances.

In the past various methods have been devised 5 of positioning concrete and similar materials with a view of obtaining a compact formation. It has been found, however, that, with concrete which has been positioned in accordance with the latest improved methods of vibrating the concrete 10 from the top as it is placed, considerable weakness is encountered adjacent the bottom of the slab. In fact, when sections have been removed and tested it has been found that in many instances a 6" slab of concrete only tests as the 15 equivalent of a 4" beam, and the weakened portion of the slab has been found to be at the base. In other words, the bottom portion of the slab as positioned was honeycombed and not compacted properly. With a view of obtaining a slab 20 of concrete which would have a strength equivalent of a beam of concrete of the same thickness, the present means and method of vibrating the concrete from the base has been devised.

It is one of the objects of the invention to provide 25 a method of positioning plastics wherein the body of material being positioned is vibrated from the base so that it is compacted uniformly throughout.

Another object of the invention is to provide 30 a method of compacting a slab of plastic material which is positioned by vibrating the entire body as it is being deposited.

It is also one of the objects of the invention to 35 trowel the base of a concrete slab while the slab is being formed and positioned.

Another object of the invention is to provide an improved method of positioning concrete 40 which includes depositing the plastic material upon a vibrating apron from which it is placed in its final position.

Another object of the invention is to provide an improved apparatus for positioning plastics 45 which includes a vibrating platform which can be moved along the surface where the plastic is being positioned.

Another object of the invention is to provide a base upon which a vibrating table is positioned for the purpose of compacting concrete immediately prior to its placement in final position.

Another object of the invention is to provide 50 a method of placing concrete which consists in compacting the material from the base so that the strength of the slab will be uniform throughout.

Another object of the invention is to provide 55

a platform which is adapted to be vibrated either from below or above for the purpose of compacting a plastic mass which may be positioned thereon.

Another object of the invention is to provide, 5 in combination with a vibrating platform, a means of removing the compacted plastic mass therefrom.

Still another object of the invention is to provide, 10 in combination with a concrete mixing machine, a vibrating platform upon which the mixed concrete is adapted to be discharged.

Another object of the invention is to provide 15 a method of positioning concrete by removing a table from beneath the deposited material and to immediately finish the top surface so that the slab is completed.

Various other objects of the invention will readily appear to those skilled in the art when the 20 following description is considered in connection with the accompanying drawings and it is intended that the invention shall take various forms and modifications.

Fig. 1 is a top plan view of one form of apparatus used in practicing the invention. 25

Fig. 2 is a top plan view of a modified form of the table or platform used in positioning the concrete.

Fig. 3 is a longitudinal sectional view through 30 one form of the platform, taken on the line 3—3 of Fig. 1.

Fig. 4 is a longitudinal sectional view taken on 35 the line 4—4 of Fig. 2, and showing a table which is resiliently mounted for the purpose of compacting the concrete.

Fig. 5 is a longitudinal sectional view of another form of the invention wherein the vibrating mechanism is disposed longitudinally of the platform and wherein a layer of protective material is applied to the underside of the concrete at the 40 time it is positioned.

Fig. 6 is a transverse sectional view showing another form of the invention.

Fig. 7 is a transverse sectional view on the line 45 7—7 of Fig. 2, illustrating one form of mechanism for vibrating the concrete and removing the same from the platform.

Fig. 8 is a side elevation of the complete combination showing the mixing machine, the vibrating platform and the deposited material. 50

Fig. 9 is a detailed sectional view taken on the line 9—9 of Fig. 2, showing one form of the vibrating element which may be used in practicing the invention.

Fig. 10 is a detailed section view taken on the 55

line 10—10 of Fig. 2, and showing one form of the invention for oscillating the table to compact the concrete.

Fig. 11 is a broken detail view of a clutch mechanism which may be used in manipulating the vibrating table.

Fig. 12 is a broken sectional view showing one form of the invention which may be used in assisting in the removal of the concrete from the 10 vibrating platform.

Fig. 13 is a broken sectional view showing the platform mounted on resilient blocks to permit its vibration.

The invention will be best understood by having reference to Fig. 8, wherein one form of mixing machine is indicated generally at 2. It is to be understood that the form of machine used in mixing the plastic is immaterial, as far as the present invention is concerned. It is, however, 15 desirable to utilize a machine which can both mix and discharge the material; the machine illustrated is one in general use, the operation is generally understood, and a detailed explanation is not believed to be necessary. It is contemplated that the machine will be capable of discharging the mixed material a short distance from the machine. In the mechanism shown, a discharge bucket or carrier 3 has been shown, which is arranged to carry a charge of material along the beam support 4, so that it may be distributed 20 in the general vicinity of the table or platform 5. The irregular contour of the deposited material is indicated generally at 6.

The present invention is particularly related 25 to the means and method of depositing the material, and one form of the means includes the apron or table 5. In Fig. 8 this apron is disposed upon the subgrade 7, and between the forms 8, which define the slab which is to be formed. The 30 table is preferably arranged to rest upon the subgrade and may be provided with an inclined upper surface 9, which receives the charge of plastic material 10. Suitable side boards or guides 11 may be arranged adjacent each side of the table 35 to confine the plastic material until it has been compacted, or until it is practically discharged from the top of the table.

It is intended that the platform 5 may be moved periodically in accordance with the general practice of moving the machine 2 after a batch or 40 several batches of concrete have been deposited upon the subgrade. With this end in view a cable or cables 12 are attached at 13 to the forward end of the platform 5 and are connected to the machine 2. A reel 14 is provided on the machine to carry the cable 12. One form which this reel 45 may assume is shown in Fig. 11. If the platform 5 is to be maintained at a constant distance from the machine 2, of course, it may be permanently connected to the machine 2 with a length of cable. It is, however, contemplated that the table 5 may be moved continuously while the concrete is being mixed and deposited thereon, so that there would be a continuous discharge 50 from the rear end 15 of the platform or table. With this in mind the reel 14 is provided with a clutch 16, which is manipulated by a handle 17. A clutch shaft 18 may be arranged for rotation by the power unit of the machine 2 at a rather slow 55 speed. Thus when the machine 2 is moved forward the clutch 16 would be disengaged so that the platform 5 would remain stationary on the subgrade. When the mixing of the material was begun the clutch 16 could be again engaged with 60 the reel 14 so that the cable 12 would be slowly

drawn in. This would cause a slow movement of the platform 5 along the subgrade so that it would be withdrawn from beneath the slab of material 10, which was being formed. It is contemplated that either the step by step movement 5 of the platform or continuous movement of the platform may be practiced.

By having reference to Fig. 1, the general arrangement of one form of the platform can be seen. This platform has connected thereto the cables 12, which have been previously described. This platform 5 is disposed between the forms 8, which define the width of the slab of material which is being positioned. While the invention is being described as applied to the placing of a strip or slab of plastic material it is contemplated that it may be used in building construction, floors, roads, pavements, or under any other suitable circumstances where a considerable quantity of material is to be placed. The platform 5 is disposed between the forms 8 and the weight thereof preferably rests upon the subgrade 7. The forward end of the table, however, is provided with a screed or grader blade 20, which is arranged to give a final smoothness to the subgrade. This 15 screed 20 may be of the form shown in Fig. 3, where it serves as an integral part of the forward end of the table 5, or it may be of the type shown in Fig. 2 or 4, wherein it is more or less of an independent construction, which is arranged to be 20 mounted on a carriage 21. A carriage 21 is also shown in Figs. 1 and 3, but it is not intended that this carriage shall support any material amount of the weight of the table because it is desirable to have a considerable portion of the weight of 25 the table applied to the subgrade for the purpose of compacting the subgrade during the placing of the concrete.

It is contemplated that the table 5 may be vibrated before and during the time that the concrete is being deposited thereon, with a view of 30 vibrating the concrete mass while it is in plastic form in order to obtain a compacted mass which will have an effective beam strength of the thickness of the slab. In order to obtain vibration of the platform various expedients may be employed. The present invention involves several such expedients, one of which is illustrated in Figs. 1 and 6. This form of vibration includes a source of power such as a motor or other element 22. 35 This element tends to rotate a shaft 23, which is mounted in the bearings 24, carried by either the base 25 of the platform or by the upper surface 26 thereof. In Fig. 1 the shafts are shown as being mounted upon the base 25. They may, however, be mounted upon the partitions 27, which serve as spacers between the base 25 and the top 26. In either event, it is intended that the shafts 23 will be provided with eccentric weights or members 29. These weights may be positioned, as 40 shown in Fig. 1, at different distances along the shaft 23, so that when the shaft is rotated by the power unit 22 considerable vibration will be imparted to the shaft and in turn to either or both the base 25 or the top 26.

Fig. 1 shows the top 26 broken away to illustrate the mounting of these vibrators inside of the platform. The shafts 23 preferably extend entirely across the platform, as seen in Fig. 1, and as many as desired may be positioned in the table 45 or platform. It is not contemplated that vibrators will be needed in each of the compartments formed by the partitions 27 and particularly is this true adjacent the end 15 of the platform. The greatest vibration is preferably had adjacent the 50

forward end of the platform where the plastic is first positioned. It seems obvious that the end 15 will be subjected to more or less vibration because it is integral with the remainder of the platform. If the elements 22 are electric motors, of course, a suitable wiring connection will be made, but it is intended that these small power elements may use compressed fluid or be driven by any desired mechanical means. While the invention has been shown in Fig. 1 as embodying a separate power drive for each of the shafts 23, it is contemplated that a large power unit may be provided to drive all of the shafts, if desired.

It is intended that the eccentrics 29 will be rotated or vibration will be otherwise imparted to the top 26 of the table while the concrete or plastic is thereon. If the surface 26 is inclined, as seen in Figs. 1, 3, 5 and 8, it is believed that, due to the vibration and the inclination of the table, the concrete will gradually travel along the table and be discharged from the end 15 directly onto the subgrade. It is intended that the taper of the table will be such that the edge 15 will be rather thin and will not break up the formation of the slab, which has been compacted due to the vibration. As seen in Fig. 8, when the material is discharged the surface thereof is rather irregular, as at 6, and may be spread around to some extent directly after it is discharged, but it has been found that the vibration of the table tends to more or less level the material and distribute it in an even uniform slab. The vibration from the base causes settling of the material so that honeycombing and voids are practically eliminated. The material as discharged from the end 15 of the table is compact and solid, and, after it has set, tests show that a beam strength of equivalent of the thickness of the slab has been obtained, whereas, when slabs are placed by other methods, the beam strength obtained varies in amounts less than the thickness of the slab by as much as 50%.

It is intended that the speed of vibration may be varied as desired, because, if the vibration is at too rapid a rate, a different arrangement of the materials in the concrete has been obtained. If the vibration is too slow other objections appear and it is intended during the development of the invention to vibrate the platform and different parts of the structure in accordance with the results desired, because it is contemplated that under some circumstances one type of concrete is desirable, whereas under other circumstances a different density or texture may be desired. It is thus intended to vary the process of positioning the material in accordance with the circumstances which are present.

Fig. 8 shows in combination with the device a surface finishing mechanism 30. This machine may be mounted to travel on the forms 8, or to be connected to the machine 2 for movement therewith, or it may be mounted in any other desired manner. It is the intention, however, to finish the surface of the concrete 10 directly after the tail 15 of the table has been moved from beneath the slabs. The finishing machine 30 may take any desired form, it merely being the object of the present invention to have a finishing machine present which will complete the treatment of the slab of material at the time it is positioned.

It is to be understood that different forms of structure for causing vibration or movement of the table 5 may be employed. Fig. 1 shows the eccentric elements 29 which will impart to the table a vibration to cause compacting of the concrete.

These vibrators are positioned transversely of the table. Fig. 5 shows a somewhat similar construction wherein the motor or drive element 22 is positioned inside of the head of the table with the grader or screed 20 positioned on the head. The shafts 23 are arranged longitudinally of the table 5 and extend as far as desired along the length of the table. This form of the invention may be more satisfactory where a comparatively thin table is desired, because the motor 22 being 10 the largest element is positioned at the head or the thick end of the table and it is only necessary to have sufficient height between the top and base of the table to permit the rotation of the eccentrics 29. Fig. 5 shows the shaft 23 as extending 15 part way along the table but it is intended that it may extend the entire length of the table, if desired.

Fig. 3 shows a section of the form of the invention of Fig. 1 and shows the shafts 23 in section as 20 well as the arrangement of the vibrators 35, two of which are positioned upon the forms 8 and arranged for movement either with the table 5 or independently thereof. These vibrators 35 are best seen in plan elevation in Fig. 1 or 2, and 25 preferably include a vibrating element 36, which is mounted upon a blade or contact element 37.

Fig. 9 shows a section of the vibrator 36 wherein in the housing 51 is mounted upon the contact element 37. Mounted in the housing 51 is a power 30 unit or drive element 52 which rotates a shaft 53, which shaft is in turn mounted in the bearing 54. An eccentric weight 55 serves to cause the vibration of the housing 51 and in turn the contact element 37. This is merely one form which the vibrator may take and this form may be used in other locations throughout the apparatus. Fig. 7 shows the contact element 37 as being supported by a cross beam 38, but is arranged for vertical reciprocating movement with respect to 40 such beam. The beam 38 is supported by the carriages 39. The blade 37 will move vertically up and down in accordance with the vibration of the eccentrics which constitute the vibrators 36. While the contact element 37 has been shown as 45 a solid blade in Fig. 7 it is intended that it may assume the form of rods or columns which tend to contact the surface 26 of the platform 5. A spring such as 40 is provided to assist in quickly returning the blade to contact with the platform 50 during its vibration.

If a solid blade is used, it is intended that the concrete will be discharged from the table in batches. As seen in Fig. 3, one batch would be accumulated in the area 41 ahead of the first 55 vibrating element during the same period that a previous discharged batch was being vibrated in the area 42 on the center portion of the platform. During this period the platform would remain stationary except for its vibration. When 60 the batch of concrete had been compacted properly, then the blades 37 would be held stationary while the table 5 was moved from beneath the blades. If desired, however, the blades could be used to assist in vibration of the table to compact the concrete and could then be raised while vibration of the table continued to discharge the batch. It is contemplated that either manner of discharging the concrete may be practiced. If 65 however, the contact elements 37 are in the form of rods or plungers, the carriages 39 may be attached to the carriage 21, so that they will move as a unit. Then, during the vibration of the table and the vibration of the contact elements 37, the concrete or plastic will pass around the rods or 70 plungers. The carriages 39 may be attached to the carriage 21, so that they will move as a unit. Then, during the vibration of the table and the vibration of the contact elements 37, the concrete or plastic will pass around the rods or 75

plungers and can be continuously discharged from the table. It is intended that the table may be used in any form desired with or without the use of the vibrators 35, and the blades or plungers 37. These have been added for purposes of disclosure to explain the uses of the structure in connection with the present method of compacting the concrete from the base. Power for the vibrators 35 may take any form, as described in connection with the elements 22 used to operate the eccentrics 29.

Figs. 2 and 7 show another form of table which may be employed and wherein the table is constructed in longitudinal segmental portions 45. A plurality of these segments or sections are seen in Fig. 2 and are disposed side by side to form the complete table. Fig. 7 shows the arrangement for overlapping the adjacent segments wherein one portion of each segment is arranged to overlap the adjacent edge of the next segment. Any other desired form of connection may be had at this point, however. Each of the segments 45 is arranged for horizontal oscillation by means of a shaft 46, which will be rotated by a power unit 47. The connection between the shaft 46 and the segments 45 may be seen in one form in Fig. 10, wherein an eccentric cam 48 is mounted on the shaft 46 and causes oscillation of a connecting rod 49. It seems obvious from this construction that the section 45 will be caused to move to the left and right as viewed in Fig. 2 and in this manner shake or vibrate any charge of concrete which is thereon. The cam 48 may be so arranged that the movement in one direction will be different from the return motion. Thus the charge of concrete will be caused to adhere to the table when moving in one direction, but the movement of the table will be so fast in the opposite direction that the inertia of the concrete will cause it to move a short distance with respect to the table. When this form of the invention is used the table may be mounted upon suitable rollers to permit oscillation thereof or it may be mounted upon springs such as 50, best seen in Figs. 4 and 10.

It is intended that the oscillation of the table shown in Fig. 2 may occur in combination with the vibration as shown in either Figs. 1 or 5, or the table may be vibrated by the surface vibrators shown in all of the figures except Fig. 5. As previously stated, it is intended that the table may be vibrated by means of the devices placed inside of the table or it may be vibrated by the contact members 37 striking the surface of the table, or both forms of vibration may be used with or without the oscillation of the table by the eccentrics 48.

Fig. 4 shows the platform 5 with the springs 50 therein, but wherein the top surface of the platform is disclosed as practically level. When the invention is so practiced, the end of the table will be inclined as at 57 in order to permit the concrete to move gradually onto the subgrade.

Fig. 13 shows a broken detail section of another form of the invention wherein the base 25

is separated from the top 26 of the table by means of a plurality of resilient members or blocks 58. These members may be formed of rubber so that vibration of the top with respect to the base may be had. When this form of the invention is used, vibration of the top 26 may be accomplished by use of the vibrators 35 and the contact members 37 to impart vibration to the table by engaging the surface.

Figs. 5 and 6 show another arrangement of the apparatus wherein a layer of paper or other suitable material 60 may be passed onto the surface of the table 5 prior to depositing the concrete on the table. Thus the concrete would be deposited on top of this layer of protective material. This material may be a waterproof paper or other substance and will serve as a protection for the table while the concrete is being laid and serve to confine the lower surface of the slab to a uniform elevation and to hold the material in place until it has set. One of the principal objects of this material is to reduce the friction between the concrete and the table. Thus, as the table is moved along the paper or other material is unrolled from the reel 61 and permits the table to be moved readily from underneath the load of concrete, it is intended that water or other fluid may be forced in beneath the layer 60 of paper or that the paper could be suitably coated so that it would be lubricated and permit sliding of the table from beneath the material.

Fig. 12 shows a detailed construction of the table wherein a flow of water or other fluid may be had on the surface 26 with a view of assisting in the removal of the mass from the table. Fig. 12 shows a plurality of pipes 63, which are arranged to discharge through the openings 64 onto the surface of the table. These pipes may be positioned throughout the length of the table or only adjacent the tail end 15, it being intended that water will be forced through these openings so that it will serve to readily permit withdrawing of the table 5. It seems obvious that a considerable number of openings 64 will be provided across the table.

While various forms of the invention have been shown and described, it is contemplated that broadly the invention embody a means and method of positioning plastics wherein a table is removed from beneath the material so that it will be placed in position in a compacted condition so that the base will be smooth and of the proper density.

What is claimed as new is:

A process of forming concrete roadways including depositing the plastic concrete on a sheet of supporting material, agitating the sheet of material and the concrete thereon to compact the concrete and form a bond with the sheet of material, and lowering the sheet of material with the superposed formed slab of concrete thereon to the subgrade.
